UNITED STATES PATENT OFFICE.

DANIEL C. MULVIHILL, OF HANNIBAL, MISSOURI.

RAMMER.

1,330,086.

Specification of Letters Patent. Patented Feb. 10, 1920.

Application filed July 3, 1919. Serial No. 308,555.

To all whom it may concern:

Be it known that I, DANIEL C. MULVIHILL, a citizen of the United States of America, and resident of Hannibal, county 5 of Marion, and State of Missouri, have invented certain new and useful Improvements in Rammers, of which the following is a specification and which are illustrated in the accompanying drawings, forming a 10 part thereof.

The object of this invention is the provision of a rammer or weight which may be placed upon the top of a cope, such as disclosed in a copending application filed by 15 me June 23, 1919, for a mold forming apparatus, Serial No. 306,050, and which is also described in said application. The object of the rammer is to obviate the necessity of hand tamping or repressing the sand 20 in the portions of the cope referred to between the partitions or bars therein disclosed.

In the accompanying drawings:

Figure 1 is a plan view of the device; 25 Fig. 2 is a section taken on the line 2—2 of Fig. 1; Fig. 3 is a side view of the device seated upon the table of a jolting machine; and Fig. 4 is a bottom plan view of the ram- 30 mer.

The invention is illustrated in connection with the molding of car wheels, and 10 of Fig. 3 represents the table of any usual type of jolting machine. 11 is the base of a 35 stripping plate, the details of which are disclosed in my copending application above referred to. 12 is a stripping ring for use with such plate, and 13 designates steady pins placed through projections 14 on the 40 chill 15 which forms a part of the cope. 16 is the internal ring of the cope, said cope comprising ring 16, an inner ring 17, and partitions or bars 18. These bars, as well as ring 17, are preferably chamfered at 45 their lower edge, as indicated at 19 and 20, Fig. 2.

The purpose of the bars or partitions is the division of the sand into smaller masses which may be compacted sufficiently to prevent drops when the form is lifted. At 21

is indicated a gate-forming implement, the details of which are disclosed in my copending application above referred to. A weight or rammer, as 22, which forms the special subject-matter of the present invention, may 55 take the form illustrated in Figs. 2 and 4. When so constructed the rammer comprises an annular ring, as 23, with blocks, preferably of wood, as 24, secured to its lower surface, as by screws 25. The blocks are so 60 located and proportioned as to size as to leave channels, as 26, between them when secured to the ring, which channels, when the rammer is in use, will fit over the bars 18.

When the cope is placed upon the jolting 65 machine and filled with sand, and the rammer placed upon the top of the cope, it will, by the mere action of the jolting machine, compact the sand sufficiently so that the mold may be stripped from the pattern and 70 lifted successfully without the occurrence of drops.

I claim as my invention—

1. The combination of a cope having bars separating the space within the cope into 75 compartments, a weight having projections thereon adapted to enter said compartments and compact the sand when the cope is jolted.

2. The combination of a cope divided into 80 compartments open at the top, and a weight having projections adapted to enter said compartments and compact the sand therein.

3. A weight comprising an upper weight- 85 ing member, and projections on said mem- ber separated from each other adapted to enter compartments of a cope.

4. A rammer comprising an annular weight- 90 ing ring, blocks secured to the lower surface of said ring, said blocks separated from each other forming channels adapted to fit over the bars of a cope.

5. A rammer comprising an annular weight- 95 ing ring, ramming blocks of uniform size and shape secured to said ring so as to leave channels between the blocks, such channels adapted to fit over the bars of a cope.

DANIEL C. MULVIHILL.
